UNITED STATES PATENT OFFICE.

ANDREW M. LOCKETT AND ANDREW M. LOCKETT, JR., OF NEW ORLEANS, LOUISIANA.

GAME APPARATUS.

1,203,021.

Specification of Letters Patent. Patented Oct. 31, 1916.

Application filed December 27, 1915. Serial No. 68,678.

To all whom it may concern:

Be it known that we, ANDREW M. LOCKETT and ANDREW M. LOCKETT, Jr., citizens of the United States, residing at New Orleans, in the parish of Orleans and State of Louisiana, have invented certain new and useful Improvements in Game Apparatus, of which the following is a specification.

This invention relates to an apparatus by means of which the game of golf may be played indoors, and certain features of the apparatus are adapted for playing similar games in which an object is moved or driven about on a field.

The principal object of this invention is to provide an inexpensive game apparatus which may be learned easily and which simulates the game to be played.

Another object is to provide an apparatus in which the element of skill is increased as much as possible, giving the players the opportunity of using their judgment in the control of the club used and the stroke given the ball, similar to that in actual play on the golf links.

Other objects and the novel features of the invention will be apparent from the following description taken in connection with the drawing in which:

Figure 1 is a plan view of one of the sections or game boards embodying the invention; Fig. 2 is a plan view of an indicator embodying the invention; Figs. 3^a and 3^b are enlarged views illustrating parts of the indicator, showing the ball and projectile member in place; Fig. 4 is a transverse sectional view of the indicator, on the line IV—IV of Fig. 3^a, showing the ball and projectile member in end elevation; Fig. 5 is a perspective view of the ball and projectile member; Fig. 6 is a view illustrating a mallet which may be used to strike the projectile member; Figs. 7 and 8 are cross-sections of modified forms of the indicator when a ball is employed, and Fig. 9 illustrates one of the pins or markers to designate the location or lie of the ball on the game board when such a marker is employed.

The apparatus consists of a board or series of boards constituting the golf course. The first hole of the golf course is illustrated on the board 10 in Fig. 1, and it will be understood that in playing a game over a nine hole course there will be eight more of these cards, while in order to have a com-

plete eighteen hole course there will be seventeen more cards or boards. These nine or eighteen boards or cards 10, may be arranged in their proper relation to each other, detached from one another, or united into one larger board or card, without departing from the spirit of the present invention. The holes are different as to distance and to physical features of the course. 60 Some of the holes are shorter and some are longer, but all the cards are preferably of uniform size, the scale of distances being modified to suit the space. The board or boards, are ruled longitudinally and transversely by the parallel lines 11 and 12, forming squares, the dimensions of which bear a certain relation to the dimensions of the golf course. The distances may or may not be indicated by marginal figures. For convenience, the direct line between the tee and the putting green has the distances marked thereon, as shown at 10^a. The tee, the fair green, the hazards and all other physical features of this character which appear on the golf course, the putting green and the hole, are represented on the boards by suitable symbols, drawings or bas relief miniature reproductions, the purpose being to represent on the board on a suitable scale a 70 map or reproduction of an actual golf course. 75

It is manifest that with either a large board or with the multiple board equipment any number of players can engage in the 90 game by following each other in the same manner as is done in an actual game of golf.

Small holes 10^b may be provided if so desired at all the intersections of the longitudinal and transverse lines 11 and 12 as indicated for example in the upper left hand corner or section of Fig. 1, to receive the pins 13, one of which is shown in Fig. 9. There are as many pins as players, and of 95 different colors, serving as position markers 10^c to represent the lie of the golf balls after each stroke.

The indicator by means of which the distance the ball is driven is determined comprises a long rectangular block 14 the top 105 side of which has two strips 15 and 16 secured thereto. Each strip has longitudinally and transversely extending lines thereon dividing the top surfaces of the strips into spaces in which figures are printed. 110 The figures are thus arranged in columns and cross rows and are intended to represent

the distances which the ball is driven by different clubs selected by the players. At one end of each column is the name of a club used in the game, and in the present illustration there is a column each for the driver, brassy, mid-iron, mashy, niblick and putter, which are the clubs used in an ordinary game of golf.

The indicator or block 14 has a channel 17 extending longitudinally thereof from end to end of the block, one end thereof being closed by the plate 18. The channel 17 is located midway between the sides of the block and opens by a narrower channel 19 in the top face of the block 14 between the strips 15 and 16. The channel 17 constitutes a guideway for the projectile member or weight 20, made of any suitable material. The projectile member has a stem 21 rigidly secured thereto, and said stem extends through the narrow channel 19 and carries the ball 22 on the outer end thereof. The ball 22 simulates a golf ball in the present instance, and in other games, it simulates 25 the object which is knocked about over the game field. The end of the narrow channel 19 is closed by a plate 23 which covers the end of the block 14 and has a hole registering with the end of the channel 7 in order that the reduced end 20' of the projectile member may project from the channel 17. The shoulder 20^b limits the outward movement of the projectile member.

The mallet 24 illustrated in Fig. 6 is provided with a suitable handle and a rubber or wooden head 241, and is used to drive the projectile member 20 longitudinally of the channel 17. However, the ball may be flipped with the fingers or may be projected 40 or driven in any other way the player may desire.

It will be seen that with this construction a player can make as many as 75 or 80 different strokes with each club, and the control of these strokes is quite possible within 45 limits will make the game capable of bringing in great skill. It is not only necessary to exercise judgment in the choice of the kind of club to be used, but also in the force 50 with which the ball is projected with the club.

While we have shown a projectile member or weight 20 of the form shown in Fig. 5 as applied to the indicator shown in Fig. 55 3^a, said projectile member may be changed to a simple form of ball or sphere 20^a of a diameter less than the width of one of the sub-divisions on the indicator 15 which permits said sphere or ball to move back and forth in a channel 17^a of rectangular cross section as shown in Fig. 7, or a channel 17^b, of circular cross section as illustrated in Fig. 8, without being displaced from the indicator 14. In each case the surface of the 60 sphere or ball 20^a projecting beyond the 65

outer plane of the plate 23 is capable of receiving a variable impact and be projected along the slot different distances for purposes as heretofore explained.

The manner of playing the game will in general be as follows: The player whose turn it is to play will place the pin representing the golf ball on the tee and will then determine from the distance he wishes to make, the club he will use in making the stroke, being guided in this selection by the distance and the physical obstacles on the green. Suppose that the case is one where the hole is over 400 yards from the tee. In such a case he would select a driver. He will then strike the projectile member with the mallet 24, or flip of the finger, or any other means, and with a force calculated to send the ball opposite a figure in the driver column of the indicator at which he will be on the green and free of obstacles. Suppose that the ball is projected opposite the mark "180-20R", and indicated at "A" of Fig. 3^b. This means the player gets 180 yards of distance toward the hole and 20 yards to the right of a direct line, and he sets the marker at the point indicated. Numerous other strokes are possible. The new location of the ball is on the fair green, but may have been in a bunker, in high grass or in any other difficulty which may exist on the course. At his next turn, the player must choose a club which, in an actual game it would be practicable to use. Being on the fair green he would use a brassy, but if he had landed in a bunker he would be compelled to use either a mashy or any other club which the player feels justified in using. The projectile member 20 is returned to its normal position and is struck again with the mallet 24, driving the ball 22 opposite a figure in the "mashy" column, or in the column of the club selected for the stroke and the marker will be moved accordingly. Should the projectile member 20, or sphere 20^a, come to a stop at the upper end 15^a of the indicator 15 the stroke will be counted as a "foozle" and no advance of the ball will be made on board 10. In the use of the sphere or ball 20^a should said sphere or ball project over two of the divisions, on the indicator 15, the lower division of the club selected is the stroke counted.

From the foregoing description it is believed the complete game will be understood. Any suitable rules may of course be adopted for playing the game.

It is to be understood that while the invention has been shown and described in detail as applied to a golf game apparatus, it 125 is only intended to restrict the scope of the invention to the appended claims.

What we claim is:

1. An apparatus for playing a game in which an object is knocked about on the 130

game field by differently constructed clubs, comprising a board bearing thereon a plurality of columns of figures representing distances which the object is knocked on the game field by different clubs, each column being designated by the name of a particular club, and an object adapted to be projected longitudinally alongside of said columns of figures to positions opposite cross rows of figures so as to indicate the distance the object has been knocked in the game by the particular club selected.

2. An apparatus for playing a game in which an object is projected about on a game field, comprising a board bearing thereon a column of figures separated by transverse lines and representing distances on the game field, said board having a slideway extending longitudinally of the column of figures, a member simulating the object projected about the game and a weight connected to said member and adapted to be projected along said slideway, said weight carrying said member with it when projected to positions opposite figures in said column so as to indicate the distance the object has been projected in the game.

3. A golf game apparatus comprising a member bearing a representation of at least a part of a golf links, a board bearing a plurality of columns of figures representing distances on the golf links, the columns of figures being designated by the names of different golf clubs, an object representing a golf ball adapted to be projected longitudinally of said columns of figures to positions opposite cross rows of figures to indicate the distance the ball is driven by the club selected, and means whereby said object may be projected with a force depending on the judgment of the player.

4. A golf game apparatus comprising a member bearing a representation of at least a part of a golf links and having intersecting lines thereon, the intersections represent-

ing possible points to which the golf ball may be driven, a board bearing a plurality of columns of figures representing distances on the golf links and having a guideway extending longitudinally of said columns of figures, the columns of figures being designated by the names of different golf clubs, an object representing a golf ball adapted to be projected longitudinally of said guideway to positions opposite cross rows of figures to indicate the distance the ball is driven by the club selected, markers adapted to be placed at said intersections to indicate the point on the links to which the ball is driven, and means whereby said object may be projected with a force depending on the judgment of the player.

5. A game apparatus comprising a game board bearing a representation of a game field, an indicator bearing a column of figures representing different distances on said game field, said indicator having a channel in the body thereof extending longitudinally of said column of figures and constituting a guideway, a member adapted to be projected along the said channel, a device simulating an object used in playing the game and rigidly secured to said member said device being disposed outside said channel above the indicator and adapted to be projected with said member to positions opposite figures in said column so as to indicate the distance the object has been projected in the game, and means whereby said member may be engaged and projected along said channel with a variable force depending on the judgment of the player.

In testimony whereof we affix our signatures in the presence of two witnesses.
